US0D1046129S

(12) **United States Design Patent** (10) **Patent No.:** **US D1,046,129 S**
(45) **Date of Patent:** **** Oct. 8, 2024**

(54) **END EFFECTOR FOR A SURGICAL INSTRUMENT**

5,688,270 A 11/1997 Yates et al.
5,693,051 A 12/1997 Schulze et al.
5,697,949 A 12/1997 Giurtino et al.

(Continued)

(71) Applicant: **Bolder Surgical, LLC**, Louisville, CO (US)

FOREIGN PATENT DOCUMENTS

(72) Inventors: **Christopher Deborski**, Denver, CO (US); **Joseph Bucciaglia**, Boulder, CO (US); **Timothy Crowley**, Arvada, CO (US); **Russell Hempstead**, Lafayette, CO (US); **Casey Kuchta**, San Jose, CA (US); **Ryan Smith**, Thornton, CO (US); **Nathan Steketee**, Westminster, CO (US)

WO 2012/044606 A2 4/2012
WO 2015/163930 A1 10/2015

(73) Assignee: **Bolder Surgical, LLC**, Louisville, CO (US)

(Continued)

(**) Term: **15 Years**

Primary Examiner — Eliza Z Harvey

(21) Appl. No.: **29/778,612**

(74) Attorney, Agent, or Firm — Vista IP Law Group, LLP

(22) Filed: **Apr. 14, 2021**

(57) **CLAIM**

(51) **LOC (14) Cl. 24-02**

The ornamental design for an end effector for a surgical instrument, as shown and described.

(52) **U.S. Cl.**

DESCRIPTION

USPC **D24/148**

FIG. 1 is a top perspective view of the claimed design;

(58) **Field of Classification Search**

FIG. 2 is a bottom perspective view of the claimed design;

USPC D24/148, 133, 143, 146, 147
CPC A61B 18/1445; A61B 2018/0063; A61B
18/1442; A61B 2017/2945

FIG. 3 is a front view of the claimed design;

See application file for complete search history.

FIG. 4 is a back view of the claimed design;

(56) **References Cited**

FIG. 5 is a right side view of the claimed design;

U.S. PATENT DOCUMENTS

FIG. 6 is a left side view of the claimed design;

5,611,808 A 3/1997 Hossain et al.
5,624,452 A 4/1997 Yates
5,637,111 A 6/1997 Sutcu et al.
5,647,869 A 7/1997 Goble et al.
5,666,035 A 9/1997 Basire et al.
5,667,480 A 9/1997 Knight et al.
5,669,907 A 9/1997 Platt, Jr. et al.
5,674,220 A 10/1997 Fox et al.

FIG. 7 is a top view of the claimed design; and,

FIG. 8 is a bottom view of the claimed design.

The figures illustrate an end effector for a surgical instrument.

Features of the article that are not shown are disclaimed. Additionally, any features shown in broken lines are for illustrative purposes only and form no part of the claimed design.

1 Claim, 8 Drawing Sheets
